UNITED STATES PATENT OFFICE.

MYRON A. CHAMPLIN, OF WASHINGTON, DISTRICT OF COLUMBIA.

LINK BELT.

1,257,579.

Specification of Letters Patent. Patented Feb. 26, 1918.

Application filed August 2, 1917. Serial No. 184,138.

To all whom it may concern:

Be it known that I, MYRON A. CHAMPLIN, a citizen of the United States, and a resident of Washington, in the District of Columbia, 5 have invented a new and useful Improvement in Link Belts, of which the following is a specification.

My invention relates to improvements in link belts, more particularly to those track laying link belts which are used with the so-called "caterpillar" tractors, and it consists in the combinations, constructions and arrangements herein described and claimed.

An object of my invention is to provide a 15 link belt whose wearing surface is cushioned so as to take up shock.

A further object of my invention is to provide a link belt in which the cushioning member is not subjected to the tremendous 20 strain such as would be present were the cushioning member brought directly in contact with the ground. I accomplish this object by placing the cushioning members between the wearing member and the body portion 25 of the link proper.

A further object of my invention is to provide a cushioned link in which the cushioning members may be readily placed or from which they may be readily removed.

30 A further object of my invention is to provide a link belt construction in which the cushioning members are so disposed as to prevent shearing of these members due to a lateral movement of the shoe or wearing members.

Other objects and advantages will appear in the following specifications and the novel features of the invention will be pointed out in the appended claims.

40 My invention is illustrated in the accompanying drawings forming part of this application, in which:

Figure 1 is a side view of a link constructed according to my invention.

Fig. 2 is a plan view.

Fig. 3 is section along the line 3-3 of Fig. 1.

Fig. 4 is a bottom plan view of a modified form of link certain parts being sections.

Fig. 5 is a section along the line 5-5 of Fig. 4.

Fig. 6 is a section along the line 6-6 of Fig. 4.

Fig. 7 is a bottom plan view of another 55 modified form.

Fig. 8 is a section on the line 8-8 of Fig. 7.

Fig. 9 is a side view of the links shown in Fig. 8.

Fig. 10 is a side view of a portion of a link belt constructed according to my invention.

Fig. 11 is a section through another modified form of the device in which springs are used.

Fig. 12 is a section through another modified form.

In carrying out my invention I may make use of any of a number of forms of links; the preferred form is shown in Figs. 1, 2 and 70 3. In this form the link consists of a main body portion 1 which is preferably a casting having up-standing side members 2, see Fig. 3, these side members having track portions 3.

The body portion 1 is provided with rectangular sockets 4, which extend transversely of the direction in which the link is designed to move. In each of these sockets is disposed a cushioning member 5, these cushioning members being arranged to extend into registering sockets 6 in a wearing member or shoe 7. The sockets 6 are disposed in grousers or cleats 8 which contact with the ground and provide means for securing a good grip thereon.

As will be seen from the drawing, the side portions 2 are provided with ears 2^x arranged to receive bolts 9 which pass through the shoe 7, nuts 10 being provided for securing these parts together.

From the foregoing description of the various parts of the preferred form the operation thereof may be readily understood. These links are secured together by means of pivot pins 11, see Fig. 10. The pins 11 pass through the opening 12, at one end of the link. These pins are provided with square heads 12^x which are held by cotter pins 11 which pass through the square 100 heads as shown in Fig. 10 and which are bent to enter recesses 13 in the side members 2. Ribs 13^x are provided whereby the pins 11 are kept from turning. At the opposite end of the link, see Fig. 1, is an opening 14 in which is inserted a bearing sleeve 15. This bearing sleeve is designed to receive the pivot pins 11 of the adjacent link.

Referring now to Figs. 4, 5 and 6, I have shown therein a modified form of the device. 110

In this form there is a body portion which is formed of a single casting; this body portion is shown at 18. It has sides 19 having track portions 20. The under portion of the casting 18 is provided with V-shaped grouters or cleats 21 and 22, these grouters being cast integrally with the body portion. The space between the grouter 21 and the grouter 22 is provided with a plurality of cushioning members. In this instance there are three of these cushioning members, these being shown at 23, 24 and 25, in Fig. 4. Obviously, a greater or less number might be used.

In order to hold the cushioning members in position and to cover them so as to prevent injury to the cushioning members, I provide a movable tread member 26 which is arranged to telescope within the space between the grouters 21 and 22. The tread member 26 is a V-shaped plate which is held in position by means of bolts 27 which pass through the body portion 18 of the link. The construction is such that when the weight of the device comes on the tread members they will be forced upwardly so that the cushioning members will be compressed, thus tending to take up the shock. The connection of the links shown in Figs. 4, 5 and 6 to their adjacent links is the same as that already described in connection with Figs. 1, 2 and 3.

In Figs. 7, 8 and 9 I have shown a modified form of link in which a body portion 27 is provided with side members 28 having track portions 29. In Figs. 8 and 9 the link is shown in the position which it would assume when on the upper side of the endless belt. The body portion 27 is fluted or corrugated transversely with respect to the direction in which the link is moving.

The grouter in this instance, consists of a separate casting 30 which is bolted to the main body portion 27 by bolts 31. A telescopic tread member 32 is disposed within the grouter 30 and has flanges which engage similar flanges on the grouter. A cushioning member 33 is disposed between the body portion 27 and the tread portion 32.

In assembling this form of device, the tread portion 32 is first placed in position in the grouter 30; the cushion 33 is then inserted and the grouter is then bolted to the body portion 27.

In this form of the device one end of the link is provided with tubular sockets 34 arranged to receive a pivot pin (not shown). These bearings 34 enter spaces corresponding to the spaces 35 on the opposite end of the link.

In Fig. 11 I have shown another modified form of the device in which coiled springs 36 are substituted for the cushion 5 in Fig. 3, while in Fig. 12 a leaf spring 37 is secured to the tread member 7 and bears on the body portion 1.

In each of the forms disclosed there is a cushioning member to take up shocks which would otherwise be transmitted. These cushioning members may be, as stated, any suitable elastic medium such as rubber or the like, or may be springs, the idea being to have a cushion between the tread member and the body portion of the link itself to take up shocks and jars.

I claim:

1. A link belt comprising a plurality of links each having a body portion provided with a track portion on one edge of the link and a tread portion on the opposite edge and cushioning means between said tread portion and said body portion.

2. A link belt comprising a plurality of links each of said links having a body portion, integral side members carried by said body portions, track portions borne by said side members, a movable tread member, and means for cushioning the tread member, said means comprising one or more cushioning members disposed between said tread member and the body portion of the link.

3. A link belt comprising a plurality of links each of said links having a body portion, integral side portions carried by said body portion, integral track portions carried by said side portions, a movable tread member, means for guiding the tread member in its movement and cushioning means disposed between said tread member and the body portion of the link.

4. A link belt comprising a plurality of links each of said links having a body portion, integral side portions carried by said body portion, integral track portions carried by said side portions, a tread member movable toward and away from the body portion of the link, means for guiding the tread member in said movements and an elastic cushion disposed between the tread member and the body portion of the link for taking up shocks received by said tread member.

5. A link belt for tractors of the caterpillar type comprising a plurality of links, each of said links having a body portion, integral sides carried by the body portion, integral track portions carried by the sides, sockets disposed in said body portion, a tread member movable toward and away from said body portion, said tread member having sockets, the sockets in said tread member being arranged to register with the sockets in said body portion, and cushioning means disposed in said registering sockets between said tread member and said body portion for taking up shocks received by said tread member.

6. A link belt for tractors of the caterpillar type comprising a plurality of links, each of said links having a body portion, integral sides carried by the body portion,

- integral track portions carried by the sides, sockets disposed in said body portion, a tread member movable toward and away from said body portion, said tread member having sockets, the sockets in said tread member being arranged to register with the sockets in said body portion, and cushioning means disposed in said registering sockets between said tread member and said body portion for taking up shocks received by said tread member, and guide members for guiding the tread member in its movement toward and away from said body portion.
- 15 7. A link belt comprising a plurality of links each of said links being provided with a body portion, side portions carried by said body portion, track portions carried by said side portions, said body portion being provided with sockets, a tread portion movable toward and away from said body portion, said tread portion having sockets arranged to register with the sockets in said body portion, resilient cushioning means disposed in said registering sockets between said tread portion and said body portion, and guide bolts for guiding the tread portion in its movements toward and away from said body portion.

MYRON A. CHAMPLIN.
